DESIGN FOR A TOY CART

Robert C. Flynt, Winston-Salem, N. C., assignor to Ursal K. Butler, doing business as New Enterprises, Winston-Salem, N. C.

Application July 21, 1943, Serial No. 110,717

Term of patent 3½ years

To all whom it may concern:

Be it known that I, Robert C. Flynt, a citizen of the United States, residing at Winston-Salem,
in the county of Forsyth and State of North Carolina, have invented a new, original, and ornamental Design for Toy Cart, of which the following is a specification, reference being had to the accompanying drawing, forming part thereof.

Fig. 1 is a side elevational view of a toy cart,
showing my new design;

Fig. 2 is a top plan view, a portion of the handle being broken away; and

Fig. 3 is a front elevational view thereof.

I claim:

The ornamental design for a toy cart, as shown.

ROBERT C. FLYNT.
